ELECTRICALLY OPERATED FLAG SHAFT
THROWING MECHANISM

Grover C. Coil, Dayton, Ohio, assignor, by mesne assignments, to Central United National Bank, Cleveland, Ohio, as trustee

Application June 19, 1931, Serial No. 545,542

12 Claims. (Cl. 235—30)

Operators of fleets of taxicabs have, for a long period of time, realized that there was more or less so-called "high flagging" by the drivers. By "high flagging" is meant that the driver carries a passenger without throwing the taximeter flag which would place the taximeter into operation. The driver fails to throw the flag with the intention of defrauding the operating company by pocketing the money collected.

Various attempts have been made to prevent this evil by providing means which would cause the flag to be thrown into operative position when the passenger takes his seat, such as, for instance, to short circuit the motor and one patent shows mechanical means consisting of a series of complicated levers whereby the flag is thrown to its operative position when the passenger takes his seat but no means is shown in the said patent whereby the flag could be made to move beyond its operative position. It has also been proposed to provide a solenoid which, when the passenger would take his seat, would release a catch and a spring would throw the flag to its operative position.

This invention is particularly adapted for that class of taximeters in which the flag shaft does not make a complete rotation. For instance, in the patent to J. F. Ohmer and E. H. Bridenbaugh 1,136,164, patented April 20, 1915, structure is shown whereby the flag is moved by the operator from its home position for approximately 102 degrees to its operative position, which flag shaft positions the various parts of the taximeter so as to accumulate the proper fares. Means are provided so that if the vehicle should be stopped through no fault of the passenger, such as a blow-out or a prolonged traffic delay, the flag could be manually thrown from its recording position to its non-recording position which is approximately 180 degrees from its home position. When the traffic delay had ceased the flag could be manually thrown in a reverse direction to its recording position but before taking a print of the fare and other indicia which is printed by the mechanism shown in the said patent it is necessary to throw the flag to its 180 degree position or its non-recording position and then the operator is required to turn a printing hand crank which prints the record and also returns the flag and the flag shaft to their home position. This movement of the flag which is imparted by the printing hand crank is in a reverse direction to that initially imparted by the driver to the flag to throw the flag shaft into its operating position. The normal operation of

the flag would, therefore, be clockwise from its vacant or home position to its recording or 102 degree position and clockwise from this position to its non-recording or 180 degree position. When the hand crank is turned the flag is rotated anti-clockwise from its 102 degree to its zero or home position and while this is being done a record is printed on a ticket which is handed to the passenger and on a record which is retained within the machine. This invention pertains to means to automatically throw a flag such as shown in the said patent from its home or zero position to the recording position whenever the taxicab is occupied and to provide means whereby the flag shaft will be thrown into the recording position even though the flag is held against such rotation. Another object of the invention is to provide means whereby the flag will be lighted whenever the taxicab is occupied by a passenger. Other objects of the invention will appear in the detailed specification and claims which follow.

In the drawings:

Figure 1 is a right hand elevational view of the machine with a part of the casing broken away to expose certain of the gears positioned therein.

Figure 2 is a similar view of the left hand side of the machine.

Figure 3 is a front elevational view of the taximeter.

Figure 4 is a top plan view of the motor driving mechanism.

Figure 5 is a sketch of a taxicab with certain parts of this invention incorporated thereon.

Figure 6 is a diagrammatic view of the electrical system employed in conjunction with this invention.

Figure 7 is an elevational view, partly in cross-section, of the automatic means to throw the flag shaft with the flag omitted.

Figure 8 is an elevational view, principally in cross-section, on the line 8—8 of Figure 7 looking in the direction of the arrow but including the lower portion of the flag.

Figure 9 is a side elevational view of the mechanism shown in Figure 8.

Figure 10 is a rear view of a notch closing member.

Figure 11 is a rear view of the lower portion of the flag and parts mounted thereon, and

Figure 12 is a diagrammatic view of a modification of the electrical system shown in Figure 6.

The taximeter casing 1 is provided with a flag shaft 2 on which is mounted a gear 3 which meshes with and is driven by a gear 4 mounted on a stud 5, which gear 4 meshes with and is driven

by a gear 6 mounted on a stud 7, which gear 6 meshes with and is driven by a gear 8 secured to a shaft 9 which has a tongue and groove connection with a shaft 10 so that the flag shaft 2 is 5 rotated by the shaft 10. All of the said gears are of the same size so that when the flag 11 is in its vacant position, as shown in full lines in Figure 1, the flag shaft will be in its vacant position. When the flag is in its intermediate or recording 10 position shown in dotted lines in Figure 1 the flag shaft 2 will be in position so that the mechanism controlled thereby, as described in the said patent, will accumulate the fares and other data. The flag should be thrown from this intermediate 15 position to its 180 degree position, shown in dotted lines in Figure 1, which is its non-recording position. After it is thrown in this position it may be returned to its zero position by means of a gear 12 which meshes with and is driven by a 20 gear 13 which is secured by means of pins 14 to a gear 15 mounted on a shaft 16, which gear 15 meshes with and is driven by a pinion 17 secured to a shaft 18 which also has secured thereto a hand crank 19. When this hand crank is rotated 25 in the direction of the arrow (Figure 2) the flag will be rotated from its 180 degree position reversely to its zero position and the printing mechanism shown in the said patent will be operated by the said hand crank. In the taximeter, as 30 heretofore manufactured, the flag has been directly secured to the shaft 10 but I propose to provide means whereby the flag shaft will be automatically thrown to its recording position when a passenger occupies the vehicle and for 35 this reason and for reasons to be hereafter mentioned, I mount the flag rotatably on the said flag shaft.

In Figure 4, I show a conventional motor 20 provided with a motor shaft 21 on which is 40 mounted a worm 22 which meshes with and drives a gear 23 mounted on a shaft 24. Secured to the gear 23 or to the shaft 24 is a gear 25 which meshes with and drives a gear 26 secured to a shaft 27 which is housed by a housing 28 (Figure 1). A worm 29 is secured to the shaft 27 and meshes with and drives a pinion 30 secured to a stud shaft 31. A gear 32 is secured to the stud shaft 31 and meshes with and drives a gear 33 which is loosely mounted on the shaft 45 10. The inner face of the gear 33 is provided with insulation 34 for approximately 90 degrees, as shown in dotted lines in Figure 7. The gear 33 is provided with a pin 35 on which is mounted a pawl 36 having a tail 37 which may be engaged by a circular plate 38 (Figure 7) which holds the nose of the pawl 36 out of engagement with a flange 39 carried by a block 40 secured to the shaft 10 by means of a pin 41. The circumference of the block 40 is composed of fiber insulation 42 with the exception of a metal strip 43 and a brass circular plate 44 which is mounted on the insulation 42 and is, therefore, insulated from the block 40. The plate 44 may be made of any conducting material, as a matter of fact, 50 and it should extend for slightly more than 102 degrees of the circumference of the block 40. The metal strip 43, as a matter of fact, may be simply a part of the block 40 which is made of any conducting metal. Rotatably mounted on a hub 45 connecting the flange 39 to the block 40 is a notch closing member 46 provided with two circular slots 47 through which extend pins 48 carried by the block 40, which pins serve as a guiding and limiting means for the notch closing member 46. The said member 46 is provided

with a flange 49 which extends flush with the perimeter of the flange 39 carried by the block 40, which flange 49 is also provided with a notch 50 similar to the notch 51 in the flange 39. The notch closing member 46 is provided with two out-standing ears 52 and 53, the ear 52 being adapted to engage the end 54 of the circular plate 38 and the ear 53 being adapted to engage a lug 55 likewise carried by the circular plate 38. The flag 11 is loosely mounted on the shaft 10 and is 10 provided with a hub 56 provided with a circular slot 57 into which extends a pin 58. The slot 57 is approximately 102 degrees in extent. The hub 56 carries a pin 59 on which is mounted a pawl 60 having an off-set ear 61. In Figure 7, I have 15 shown pawl 60 in dotted lines in order to indicate its relative position although it would not really be seen in this figure for it is mounted on the hub 56 of the flag. The inner end of the pawl 60 is pressed inwardly towards the shaft 10 by means 20 of a spring 62. It is also provided with an oppositely extending arm 63 adapted to be engaged by a circular plate 64 which extends for approximately 102 degrees. The ear 61 when pressed inwardly by means of the spring 62 when the arm 25 63 is released will engage within a notch 65 in the block 40, the outer portion of the block being cut away, as shown at 66 in Figure 8, so as to accommodate the ear 61. A spring 67 is coiled around the shaft 10 and has its opposite ends 30 embedded in the block 40 and the hub 56 of the flag 11. A block of insulating material 68 is secured to the frame-work of the machine and on this block is mounted a conducting plate 69 having a spring contact arm 70 which engages with 35 the insulation 34 when the said insulation is adjacent the same and, if not, with the gear 33. The conducting plate 69 has also secured thereto a spring contact arm 71 which presses against either the metal strip 43 or when the block 40 40 has been rotated it presses against the insulation 42. The insulating block 68 also has attached thereto a spring contact 72 which presses against the insulating material 42 or the brass circular plate 44. The hub 56 of the flag is provided with an insulating plate 73 to which is attached a contact 74 which engages the circular plate 44. A lead 75 extends from the contact 74 to a light 76 which is housed by transparent material 77 in the hand part of the flag. 50
A source of electrical energy, such as a battery 78, is grounded and has its positive pole connected to a lead 79 connected to contacts 80, which may be any number of contacts and may be operated by the passenger stepping on the floor board or 55 sitting on the seat. In case the folding seats are used for extra passengers, similar switches could be placed within said folding seats or so as to be closed when the said seats are lowered, if desired. From these contacts a lead 81 extends to 60 the motor 20 and also to a lead 82 connected to the spring contact 72. A lead 83 extends from the motor to the conducting plate 69. The shaft 10 is grounded and as the gear 33, which is made 65 of conducting material and mounted thereon, is connected to the spring contact 70 a circuit through the said contact 70 is completed when the spring contact is in contact with the gear 33 but is broken when it is in contact with the insulating material 34. Likewise, as the spring contact 71 normally engages the metal strip 43, which is attached to the conducting block 40 which is mounted on the shaft 10, the circuit through the spring contact 71 is normally closed but as soon as the metal strip 43 passes out of engage- 70 75

ment with the spring contact 41 and the fiber insulation 42 engages the said spring contact 41, the circuit through the spring contact 71 is broken. However, both the circuits through the contacts 70 and 71 will be broken unless a passenger is occupying the vehicle and thereby closing the contacts 80. The flag is lit the moment a passenger takes his seat for the contacts 80 will then be closed and the flag will be almost instantaneously thrown so as to bring the plate 44 into engagement with the spring contact 72 and the circuit will be completed through the contact 74 and lead 75.

In operation the flag is normally in full line position shown in Figures 1 and 2 which is the same position as that shown in Figures 5 and 6. When a passenger enters the vehicle his weight closes the contacts 80 and thereby closes the circuit from the lead 79 through the lead 81 to the motor 20 and lead 83 to the spring contact 71 which, as shown in Figure 9, is in engagement with the metal strip 43 from whence the current passes to the ground through the shaft 10. When the gear 33 is in normal position, that is, with the flag in vacant position, the insulation 34 on the gear 33 holds the contact 70 out of engagement with said gear and the completed circuit is made through the contact 71 and not through the contact 70. When, however, the passenger takes his seat the motor is operated and drives the gear 33 through the train of gears shown in Figures 4 and 7. As the gear 33 rotates it carries with it the insulation 34 and the pawl 36. The insulation 34 passes beyond the contact 70 at approximately the same time that the pawl 36 engages the notch 51 as hereinafter described so that at least momentarily the circuit is completed through both the contacts 70 and 71, it being remembered that the metal strip 43 has remained stationary up until the time that the pawl 36 engages the notch 51. The tail 37 of the pawl 36 passes beyond the circular plate 38 and thereafter the nose of the pawl 36 is pressed against the flange 39 of the block 40 by means of a spring 83. When the nose of the pawl 36 reaches the notch 51 in the flange 39 it drives the block 40, moving the metal strip 43 beyond the spring contact 71, but simultaneously with this occurrence the insulation 34 carried by the gear 33 moves beyond the spring contact 70 so that the circuit is now completed through the contact 70 and gear 33 so that the motor continues to drive the gear 33 and block 40, which is secured to the shaft 10, until the shaft 10 has been rotated for approximately 102 degrees or whatever proper number of degrees which would be required to bring the flag shaft 2 into its recording position, at which time the gear 33 will have made one complete revolution so as to bring the insulation 34 into engagement with the spring contact 70 thereby breaking the circuit. The gear 33 will run on a short distance until it idles down to a stop but this distance is never sufficiently great to move the insulation out of engagement with the spring contact 70. All driving connection through the motor is now broken and the flag shaft has been rotated to its operative position through the gearing shown in Figure 1.

Normally the flag would have partaken of the motion of the shaft 10 because it is interconnected with the said shaft by means of the spring 61. If, however, the operator placed some obstruction in the way of the flag 11 so that it could not rotate, the shaft 10 would rotate anyhow against the tension of the spring 67 so that a dis-

honest driver would have accomplished nothing by blocking the flag so that it could not be moved.

If for any reason the current was off or some of the leads connected with the motor were broken so that the automatic flag shaft throwing means was inoperative, it would still be the duty of the driver to manually throw the flag to its recording position when a passenger occupied the vehicle. He can do this because the pin 58 carried by the block 40 engages the end of the circular slot 51 so that if he grasped the flag and pressed downwardly on it the end of the slot 51 would rotate the block 40 by means of the pin 58 thereby rotating the shaft 10 and the flag shaft 2. In the above mentioned instance where the driver attempts a fraud by blocking the flag against rotation, the pin 58 would move to the other end of the slot 51 and when he later turned the flag loose the spring 67 would rotate the flag 11 moving the slot 51 so that the pin 58 would again lie in the lower end thereof, as viewed in Figure 11.

If it is necessary to throw the flag to the non-recording position, as it would be if the vehicle was stopped for a prolonged period of time when it was no fault of the passenger, the flag 11 would be manually rotated to its 180 degree position, which stops the clock mechanism in the taximeter, as shown in the said patent, but if the driver should attempt to drive with the flag in this position, not only could he be detected by an inspector seeing it, but he would accomplish nothing for the fares would continue to accumulate. It is so manually rotated from its recording to its non-recording position by the operator manually rotating the flag 11 and thereby engaging the end of the slot 51 with the pin 58 thereby rotating the shaft 10 with the flag 11.

When the flag reaches its recording position, the arm 63 of the pawl 60 passes beyond the circular plate 64 and the spring 62 presses the ear 61 into the notch 65 of the block 40 so that the operator could manually move the flag back from its 180 degree position to its recording position.

The said patent shows mechanism whereby the flag cannot be manually returned from its recording to its home position without first being brought to its non-recording or 180 degree position and even then it can only be returned to its home position by rotating the crank 19 which operates the printing and resetting mechanism as shown in the said patent. None of this structure is shown in this application as it is fully shown and described in the said patent.

There is nothing to prevent the driver from printing the record and returning the flag shaft to its home position even though the passenger may continue to occupy the vehicle but if he does this, the parts will again be brought into the position shown in Figure 9 and the motor will immediately be operated a second time, charging an additional fare, so that the driver hasn't cheated anybody but himself.

As soon as the passenger takes his seat the flag light is illuminated through the lead 82, contact 72, plate 44, contact 74 and lead 75. The only reason that there is any plate 44 necessary is in case the driver would hold the flag against rotation the light would still be lit because the plate 44 is as long as, or longer, than the slot 51.

Once in a long while, a passenger might hire a taxicab and momentarily take his seat and almost immediately jump up and leave the cab. Under these conditions, it would be barely possi-

ble that the gear 33 would have rotated sufficiently so that the pawl 36 would have engaged the notch 51 and driven the block 40 a short distance but not fully operated it. The parts are 5 now in an incorrect position. The flag shaft has been partially rotated and the motor has been cut off and the flag is only a part of the way down. The driver should now manually complete the throw of the flag and when he does so he moves 10 the block 40 to its 102 degree and its 180 degree positions but this does not move the gear 33. If now I attempted to use the hand crank 19, the block 40 would be reversely rotated until the notch 51 reached the pawl 36 and the entire 15 machine would be locked up. To prevent such an occurrence I have provided the notch closing member 46 which normally moves with the block 40. Just before the block 40 has reached its 180 degree position, the ear 52 carried on the 20 member 46 would engage the lateral extension 84 of the circular plate 38 which would shift the member 46 relative to the block 40 so that the notch 50 in the member 46 would no longer be in alignment with the notch 51 in the flange 39. 25 The pawl 36 is sufficiently wide to extend over both the flange 49 of the member 46 and the flange 39 so that when we now rotate the block 40 by the hand crank 19 to move it from its 180 degree position to its home position the nose of 30 the pawl 36 cannot enter the notch 51 and, therefore, the block 40 and the shaft 10 can be returned to home position but as soon as they are returned to home position the ear 53 of the member 46 will engage the lug 55 on the circular plate 38, which will again shift the member 46 so as to bring its notch 50 in alignment with the notch 51 on the flange 39. If now a second passenger took his seat, the machine is ready to function in its 35 normal way. The ear 61 is held out of engagement with the notch 65 except when the flag is in its recording position or in some position between and including the recording position and its non-recording or 180 degree position, being held out of engagement in its home position or in 40 all positions up to its recording position by means of the arm 63 engaging the circular plate 64.

It is realized that occasionally a passenger 45 may demand a printed receipt for his fare, such as shown in the said patent, and this receipt can only be issued by operating the hand crank 19, which would return the flag to its home position. If, for instance, it was a rainy evening and the passenger did not wish to get out of the cab or to even arise from his seat and still demanded 50 his receipt, this could be accomplished by providing a contact 85 operated by the door. In the modification shown in Figure 12, if the door is opened this contact will break the circuit and the operator could, therefore, issue the ticket 55 without again starting the motor while the passenger continues to occupy the seat, providing he had the door open.

I realize that many changes may be made in 60 the specific form of the invention shown by way of illustration in this application and I, therefore, desire to claim the same broadly except as I may limit myself in the annexed claims.

Having now described my invention, I claim: 65

1. In a taximeter, a motor, a flag shaft, a gear loosely mounted on said flag shaft and adapted to be driven by said motor, means whereby said gear, when operated, automatically drives said flag shaft to its operative position, and means 70 whereby said last mentioned means is automati-

cally rendered inoperative when said flag shaft has been moved to its operative position.

2. In a taximeter, a motor, a flag shaft, a rotatable means connecting said motor and flag shaft so as to drive said flag shaft, and means 5 to automatically render inoperative said first mentioned means when the flag shaft has been moved to its operative position.

3. In a taximeter, a motor, a flag shaft, rotatable means whereby said flag shaft may be rotated by said motor, means to render said first mentioned means inoperative when the flag shaft has been moved to its operative position, and means whereby said flag shaft may be caused to rotate to its home position. 10

4. In a taximeter, a motor, a flag shaft, a gear, means whereby said gear is driven by said motor, means to connect automatically said gear to said flag shaft when said gear is rotated so as to move said flag shaft from its home position to its operative position, means to disconnect said gear from its driving engagement with said flag shaft when the said flag shaft has been moved to its operative position, and manual means whereby said flag shaft may be rotated to its home 25 position.

5. In a taximeter, a flag shaft, a second shaft, means interconnecting the said shafts, a flag, and a yieldable connection between said flag and said second mentioned shaft. 30

6. In a taximeter, a shaft, a flag loosely mounted thereon, and a yieldable connection between said flag and said shaft.

7. In a taximeter, a shaft, a gear mounted thereon, automatic means whereby said gear may be operated, a pawl carried by said gear, a flange secured to said shaft and provided with a notch engageable by said pawl to rotate said shaft when said gear is rotated, a resetting means for said shaft and flange, and means to close said notch when said gear has been partially operated when said shaft is being reset. 35

8. In combination, a flag shaft, a flag rotatably mounted on said shaft, a spring resiliently connecting said flag and flag shaft, and means 45 whereby when the flag is rotated the flag shaft will be correspondingly rotated.

9. In combination, a flag shaft, a flag rotatably mounted on said shaft, and a spring wound around said shaft and resiliently connecting said 50 flag and flag shaft.

10. In a taximeter, a control shaft, a flag, automatic means controlled by the weight of an object to rotate said control shaft to operative position, and means interconnecting said flag and shaft whereby said flag is moved by the rotation of said shaft unless the flag is restrained from such movement. 55

11. In a taximeter, a shaft, means to rotate said shaft to operative position, means operated by the weight of an object to control partially the said movement of said shaft, a flag normally rotatable with said shaft, and a means which will yield so as to permit said shaft to be so rotated even if the flag is held against movement. 60

12. In combination, an electric motor, a taximeter control shaft, means whereby said motor when actuated will drive said shaft from its "for hire" to its operative position, a flag rotatably mounted on said shaft, and a resilient connection between said shaft and said flag so that said motor when actuated will rotate said shaft to operative position even though the flag is held against rotation. 65
